MEANS FOR DISCHARGING PULP FROM BLEACHING TOWERS

John P. Rich, Nashua, N. H., assignor to Improved Machinery Inc., Nashua, N. H., a corporation of Maine

Application October 22, 1952, Serial No. 316,117

2 Claims. (Cl. 68—181)

It is an object of this invention to improve the efficiency, mechanical, hydraulic and chemical, of high density downflow, circulatory type, continuous pulp bleachers.

The above and other objects will be made clear from the following detailed description taken in connection with the annexed drawing, in which:

Figure 1 is a vertical section through a typical tower;

Figure 2 is a section on the line 2—2 of Figure 1; and

Figure 3 is a detail of one of the valves controlling each dilution nozzle.

A bleaching tower of the type here under consideration may range from 8 to 20 feet in diameter and from 15 to 75 feet high, depending on its intended capacity in tons per hour and the time during which the pulp is to remain in the tower, exposed to the bleaching action.

Inasmuch as chemical reaction is occurring throughout the time the pulp is in the tower, it is essential that so nearly as possible the pulp be removed from the bottom of the tower in the identical sequence in which it was added. There are certain other practical problems. Any particular tower is "rated" for a particular out-put but there is no guarantee that it will be operated always at that rate. In practice, for example, the tower must be capable of operating efficiently down to as low as 1/2 of its rated out-put and up to as high as 25 percent above its rated out-put. There are advantages in operating the tower at relatively high consistencies, e. g., from 10 to 20 percent solids. To be removed by pumping action, however, it must be diluted to between 2 1/4 and 4 percent solids. The removal of the dilute stock should be uniform.

In the past there have been provided hydraulic jets peripherally arranged around the tower which were intended to operate on the high density pulp mass much in the manner of hydraulic mining jets. The size and number of jets is arrived at by consideration of the water requirements under the most extreme conditions, that is: assume maximum density of the body of pulp in the tower and minimum density of the stock to be pumped out. This defines the "rated capacity." 25 percent above the rated capacity is usually selected. Such a computation will provide ample nozzle capacity to meet the worst conditions. Unfortunately, however, except during relatively brief periods of overload, such a nozzle system, for reasons which will appear hereafter, is operating below optimum efficiency.

In the past the typical nozzle has included a valve operating on the general principle of a needle valve, connected to a spring-pressed diaphragm or piston wherein the pressure of the water entering the valve moves the diaphragm or piston to withdraw the valve from its seat. Obviously the higher the pressure in the valve, the greater the opening, and vice-versa. Regulation for this type valve is accomplished by increase or decrease of header pressure as by manual setting of a throttle valve supplying the header from which all of the nozzles are fed. This means that at rates and flows less than maximum (overload conditions) the throttle valve leading to the

2

header is partially shut down, reducing the pressure in the header and consequently in the valves. Thus under most operating conditions the full pressure desirable for optimum hydraulic mining is not available.

5 There is herein proposed a new application whereby header pressure cannot only remain full but actually increase under reduced flow.

The present invention combines features of the nozzle design with certain well known characteristics of centrifugal pumps to the end that the delivered pressure and therefore velocity increases as the flow demand of the system decreases.

The present invention contemplates a control of the valves by means independent of line pressure so that velocity, which contributes so greatly to the effectiveness of the jets as "hydraulic miners," is not only undiminished but actually increased even though by independent adjustment of the valves the quantity of fluid delivered may be adjusted accurately to the demands of the particular 15 situation. This is done by placing the valves under the control of diaphragms which are subjected to independently variable air pressure. No throttle valve is provided in the line feeding the header and the valves so that full pump pressure is available at all times.

20 Referring now to Figure 1 there is shown a typical tower having a cylindrical shell 10. Pulp is supplied through an inlet 12 by conventional pulp feeding means indicated generally at 13 and will lie usually in a conically topped pile 14. The bottom of the tower is a conical formation 16 and one or more agitators 18 are placed adjacent the base of the cone 16. Dilute pulp emerges through an outlet 20 while dilution jets 22 supply the diluting and disintegrating effect.

25 As will be clear from Figure 2 the jets or nozzles 22 are mutually identical. Each is controlled by a valve 24 and all are supplied by a header 26. The header 26 receives dilution water through a line 27 from a substantially constant speed centrifugal pump 31. The valves are supplied with operating pressure by a line 28 and 30 with control pressure by a line 30. The pressure in the control line 30 is manually set at a control panel 32 by conventional means.

35 Referring now to Figure 3 there is generally illustrated a nozzle 22 in which is formed a groove or channel 34, the effective area of which is adjusted by axial movement of a tongue 36 which slides on the underside 38 of the nozzle 22. The tongue 36 is moved by a rod 40 on the opposite end of which is mounted a conical poppet valve 42 adapted when the tongue 36 is at its extreme 40 leftward movement to seat on a conical member 44 for water-tight closure of the nozzle. The rod 40 and the valve 42 are secured to a shaft 46 which passes through a stuffing box 48. Water emerges from the header 26 into a chamber 50 through an orifice 51, the chamber 50 being closed by the stuffing box 48.

45 Rod 46 is secured to a frame 52 and springs 54 surrounding rods 56 bias the whole structure, that is frame 52, rods 46 and 40, tongue 36 and associated parts, toward closing position. At one end of the frame 52 is mounted a diaphragm 58 which is clamped between a flange 60 formed in the frame 52 and a flange 62 of a cover plate 64 which, with the diaphragm 58, defines an air chamber 66. A rod 68 secures the diaphragm through a connection 70 with a substantial part of the machine. Actually the connection 70 is part of a frame similar to the frame 52. It passes through aligned openings 71 in the frame 52 and is bolted (without spring relief, however) to the member 57 which receives the bolts 56. The chamber 66 has an air inlet and outlet 72 which is connected by a line 74 with a pilot valve 76. Operating air comes to the pilot valve through a line 28 and is exhausted through a line 29. The pilot valve is actuated by air supplied 55 60 65 70 75 80 85 90 95

through the control line 30. In usual practice the operating line 28 would carry air at about 100 p. s. i. (as used herein, the abbreviation "p. s. i." means pounds per square inch) while the control line 30 would carry air at pressures between 3 p. s. i. and about 15 p. s. i. At 5 3 p. s. i., the valve would be closed. At 15 p. s. i. it would be wide open and at about 9 p. s. i. it would be half open.

In operation when, say, 9 p. s. i. is supplied to the control line the pilot valve admits the main line air 10 through the line 74 to the chamber 66. Since the position of the diaphragm 58 is fixed the entire assembly moves to the right, drawing the tongue 36 to a half open position. All of the nozzles will be adjusted simultaneously and equally. In general usage a valve is termed a "pilot valve" if it is used to control the action of another valve. Here the pilot valve 76 sets the valve 24 to provide a proper inflow and outflow of air to the chamber 15 70 to insure proper pressure on the diaphragm 58 and thus to govern the position of the tongue 36. A spring 67 bears on the right hand end of fixed rod 68 and resists movement of the pilot valve 76. The spring 67 is calibrated to yield to a predetermined position for each predetermined p. s. i. of control pressure supplied through 20 the control pressure line 30.

The nozzles perform a number of functions among which, of course, is the simple supplying of dilution water, the demand for which is quite variable as noted earlier above. They also serve to cut away and defiber the bottom of the mass of high density stock and, further, they contribute materially to the circulation of the stock at the base of the tower. Both of these last two functions are functions of velocity or, rather, the energy of the jets. As the quantitative demand for dilution water goes down, the functions of defibering and circulation become increasingly important and both of these functions, as just noted, are related to the energy rather than the quantity of the jets. Obviously, as the total flow decreases, the mass delivered by the jets decreases. Velocity, however, is a function of head and the energy of the jets is the product of mass times the square of the velocity. Accordingly, if the effective pressure of the jets, and hence the effective velocity, can be maintained or increased, the energy of the jets, being responsive to the square of the velocity and only directly to the quantity or mass, may be maintained at, or near, optimum efficiency so far as the defibering and circulating functions are concerned. 45

In the operation of centrifugal pumps, the effective head increases as the flow decreases. By controlling the valves directly and independently, full advantage is taken 50 of this characteristic, and the more the flow is reduced, the higher the head and, therefore, the velocity, which

tends to level out the delivered energy of the jets throughout a considerable range of flow. Disregarding dimensions and constants, and for ratio purposes this is justified, the energy of the jets equals flow (or quantity or mass) times the effective head.

As above noted, taking "rated" capacity as unity, the required range is from 0.5 to 1.25, hence minimum quantity is 40% of maximum. In a typical pump, the delivered head at minimum flow is 225 p. s. i. while at maximum flow it is 135 p. s. i., but the energy at minimum flow (0.5×225) is 66.5% of the energy at maximum flow (1.25×135). In conventional practice, maximum valve opening would occur at 135 p. s. i. on the pump. This would be reduced by throttling the line feeding the header. The pump pressure, to be sure, would increase, but the header pressure would decrease due to the throttle. The energy at minimum flow (volumetrically 40% of maximum) would be far less than 40% of the energy of the maximum flow as compared with the above noted 66.5% obtained by this invention.

I claim:

1. Means for bleaching wood pulp comprising a reaction tower having its axis vertical; means at the top of the tower for continuously delivering into the tower a high density mixture of pulp and a bleaching agent; said tower having an outlet adjacent its bottom; a plurality of inwardly directed, peripherally spaced nozzles adjacent the bottom of said tower but spaced vertically above said outlet; a substantially constant speed centrifugal pump for delivering dilution water to said nozzles; means connecting said pump to each of said nozzles; each of said nozzles having an outlet opening and a member movable within each of the nozzles to adjust the area of said openings; each of said members having a fluid pressure responsive device connected thereto for moving the same; a source of fluid pressure independent of said pump, and control means for applying said fluid pressure equally to all of said devices.

2. Means as set forth in claim 1 in which said control means applies fluid pressure simultaneously to all of said devices.
